(57) **CLAIM**

The ornamental design for a stand for portable device, as shown and described.

DESCRIPTION

FIG. 1 is a reduced scale front, right, top side perspective view of a stand for portable device showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference perspective view thereof with a portable device attached.

The broken line showing of a portable device in FIG. 8 is for illustrative purposes only and forms no part of the claimed design.
